UNITED STATES PATENT OFFICE.

CHARLES SHERWOOD FARRISS, OF DE LAND, FLORIDA.

DETACHABLE AND COLLAPSIBLE HANDLE FOR SAFETY-RAZORS.

1,292,449.

Specification of Letters Patent. Patented Jan. 28, 1919.

Application filed January 10, 1918. Serial No. 211,159.

To all whom it may concern:

Be it known that I, CHARLES SHERWOOD FARRISS, a citizen of the United States, residing at De Land, in the county of Volusia, State of Florida, have invented a new and useful Detachable and Collapsible Handle for Safety-Razors; and I do hereby declare the following to be a full, clear, and exact description of the invention, such as will enable others skilled in the art to which it appertains to make and use the same.

This invention relates to an improved handle for safety razors and the like, and one of the objects of the invention is to provide an improved handle, which may be detached from the safety razor or the like, and reattached in a different position on the safety razor, or reattached in a collapsed position against the safety razor.

20 A further object of the invention is to provide a device of this kind, which may be folded or collapsed in a small compass, in order to consume a small space, when stored away out of use.

25 A further object of the invention is the provision of a device of this kind, which may be manufactured at a small cost and sold at a reasonable profit.

In practical fields the details of construction may necessitate alterations falling within the scope of what is claimed.

The invention comprises further features and combination of parts as hereinafter set forth shown in the drawings and claimed.

35 In the drawings:—

Figure 1 is a view in perspective of a safety razor, showing the improved detachable handle therefor attached thereto at one end.

40 Fig. 2 is a perspective view of the safety razor showing the detachable handle connected thereto in another position extending at an angle therefrom.

Fig. 3 is a view in elevation of the safety 45 razor showing the handle connected thereto in a collapsed position, and in parallelism with the safety razor.

Referring more especially to the drawings, 1 designates a base plate or holder having on one face thereof laterally extending spaced lugs 2, which project through the apertures or openings 3 of the safety blade 4. Also projecting from the same face of the holder or base plate intermediate the lugs 2 is a threaded stud or screw 5, and 55 6 denotes a guard plate. The razor blade 4

is provided with a central opening 7, through which the screw or stud 5 extends. The guard plate is provided with apertures or openings 8, for the reception of the lugs 2, 60 and also an intermediate aperture or opening 9 for the reception of the stud or screw 5. A handle 10 is provided, and which is constructed to provide an elongated central contracted portion 11 having enlargements 65 12 and 13 at its opposite ends. Adjacent where the enlargements 12 and 13 integrally connect to the contracted portion 11 shoulders 14 and 15 are constructed. The central part of the contracted portion 11 of the 70 handle has an opening 16, for the reception of the stud or screw 5 of the base plate or holder 1, when the handle is disposed or collapsed in parallelism against the guard plate 6, there being a thumb nut 17 threaded 75 on the screw or stud 5 to hold the handle securely in place, when the safety razor is stored away out of use. The handle may be arranged as shown in Fig. 3, in which case the shoulders 14 engage the opposite ends 80 of the guard plate, to hold the handle in position and in parallelism with the guard plate, and vice versa. However, the handle may be reversed end for end to that shown in Fig. 3, or turned over and in this case 85 the shoulders 15 may engage the ends of the guard plate to hold the handle in position. When the handle is disposed as shown in Fig. 3 the guard plate and the razor blade are clamped in parallelism against the blade 90 plate or holder. One end of the base plate or holder 1 has an extension screw 18. The enlargement 12 of the handle is provided with a threaded socket 19, and threaded into the enlargement 12 at right angles to the 95 socket is a thumb screw 20. The enlargement 13 at its end is provided with an inclined or beveled face 21 and extending obliquely through the enlargement but at right angles to the inclined or beveled face 100 is a threaded opening 22. When using the safety razor the handle may be detached from the position shown in Fig. 3, and the screw 18 threaded into the socket 19, after which the thumb screw 20 is tightened 105 against the screw 18, thereby rigidly connecting the handle to one end of the base plate or holder. In this case the thumb nut 17 is threaded home on the screw 5 to hold the guard plate in place and the razor blade 110 between the guard plate and the base plate. When the handle is thus connected, the ra-

zor may be used in a manner similar to the use of the usually folding blade razor. However, on the other hand the thumb nut 7 may be detached and the screw 5 threaded 5 into the opening 22, whereby the inclined or beveled face 21 may contact with the face of the guard plate thus holding the guard plate against the razor blade, which in turn is clamped against the base plate. In this 10 case the handle is held at an angle from one face of the guard plate, whereby the safety razor, may be used in the usual way.

The invention having been set forth what is claimed as new and useful is:

- 15 1. In a device as set forth, a safety blade holder, a safety blade and guard plate, a handle, and means carried by the holder and extending through the blade, the guard plate, and the handle and having a device 20 for clamping the parts together in parallelism, means on the holder projecting through the blade and the plate to prevent turning of the plate and the blade, said handle having shoulders at either end to 25 engage either end of the guard plate to

prevent an oscillatory displacement of the handle.

2. The combination with a holder, of a safety blade guard, a right angle laterally extending screw projecting from one face of the holder and through the blade, a handle having enlargements at both ends and provided with shoulders adjacent said enlargements, said enlargements having threaded openings, either one being adapted to engage the threaded screw, the central portion of the handle having an opening to receive said screw to hold the handle longitudinally across the blade, with said opposite shoulders engaging the opposite end edges of the guard, and means for holding the guard from rotating on the screw.

In testimony whereof I have signed my name to this specification in the presence of two subscribing witnesses.

CHARLES SHERWOOD FARRISS.
